FINGER SUPPORT FOR BOWLING

Taylor Paisley, Ferndale, Mich.

Application February 5, 1953, Serial No. 335,194

5 Claims. (Cl. 2—21)

This invention relates to finger supports and more particularly to an improved finger support particularly adapted for use in the game of bowling.

As is well known, the bowling balls conventionally used in the game of bowling are provided with two or three spaced passageways which extend inwardly from the periphery thereof and facilitate gripping the ball, the ball being gripped by inserting the thumb and a portion of either one or two fingers in the spaced passageways.

Assuming that two fingers and the thumb are utilized to grip the ball, the passageways are so spaced that substantially all of the bowler's thumb and the outer end portions of the middle and ring fingers extend into the passageways while the palm of the hand, the inner portions of the middle and ring fingers, and the index and little fingers extend along the periphery of the ball. When the ball is so gripped, the middle and ring fingers are bent at an angle of approximately 90 degrees at the intermediate joints in such fingers, or the joints just outwardly of the joint between the inner ends of the fingers and the palm portion of the hand.

It has been found that in order to consistently knock down the maximum number of bowling pins, the ball should be rolled in such a manner that it curves inwardly toward the center of the bowling alley during its travel toward the spaced pins. In order to obtain such a curvilinear path of travel, it is desirable to impart a rotary motion to the ball as it leaves the hand and it is also well known that the preferred method of obtaining such rotary motion is to release the ball in such a manner that the thumb is pulled out of its passageway first while the middle and ring fingers remain bent, with the outer end portions extending into their respective passageways. The ball then rolls from the middle and ring fingers as it is released and the rotary and linear sliding motions of the ball combine to provide a curvilinear path of travel.

However, many bowlers have a tendency to straighten their middle and ring fingers before they release the ball, with the result that only a translatory motion is imparted to the ball, thus making it difficult to consistently knock down the maximum number of pins.

The principal object of the present invention is to provide a finger support particularly adapted to hold selected fingers in a bent position so as to prevent the bowler from inadvertently straightening such fingers prior to the release of the ball.

Another object of the invention is to provide an improved finger support of the indicated character which is simple in construction, economical to manufacture, durable and reliable in operation.

Still another object of the invention is to provide an improved finger support which may be readily adapted for either right hand or left hand use and which may be used without marring or otherwise damaging the bowling ball, or interfering with the hand grip on the ball.

Yet another object of the invention is to provide a

2

lightweight finger support incorporating improved means for releasably securing such support to a finger of the bowler's hand.

The above as well as other objects and advantages will become apparent from the following description and the appended claims. A preferred embodiment of the invention is shown in the accompanying drawing throughout the several views of which corresponding reference characters designate corresponding parts and wherein:

10 Figure 1 is a perspective view of the present invention secured to selected fingers of a bowler's hand gripping a bowling ball;

Fig. 2 is a side elevational view of a finger support of this invention;

Fig. 3 is a top plan view of the structure illustrated in Fig. 2;

Fig. 4 is a sectional view of the structure illustrated in Fig. 3 taken on the line 4—4 thereof;

20 Fig. 5 is an end view of the structure illustrated in Fig. 3, with the retaining means in the open position;

Fig. 6 is an end view of the structure illustrated in Fig. 3, with portions in section, and showing the retaining means in the closed position; and

25 Fig. 7 is an enlarged perspective view of the finger support illustrated in Figs. 1—6, showing the finger support positioned on a bent finger and the strap and connecting member in the closed position.

Referring to the drawing and more particularly to Fig. 1, a conventional bowling ball 10 is shown having spaced 30 passageways 12, 14 and 16 formed therein in the conventional manner. It will be understood that the present invention is applicable for use in bowling with balls having either two or three passageways and the ball 10 is shown with three passageways for the purposes of illustration.

The ball is gripped in such a manner that substantially all of the thumb of the bowler's hand extends into the passageway 12 while the palm of the hand, the index and little fingers, and the portion of the ring and middle fingers between the palm and the joints in the fingers adjacent the palm extend along the periphery of the ball. The middle and ring fingers are bent at an angle of approximately 90 degrees at the joints in the fingers remote from the ends thereof and the outer end portions of such fingers extend into the passageways 14 and 16.

The present invention provides means for supporting the middle and ring fingers in the bent position so that the bowler will not inadvertently straighten such fingers before he releases the ball. To this end, a support member, generally designated 15, is fitted on each of such fingers. Each support member is formed of a single sheet of relatively thin material, stamped or otherwise formed in the shape of an elongated, tapered cup having relatively long curved end walls 18 and 20 shaped to fit the dorsal surfaces of the finger when the finger is bent and joined at the apex by an integral portion 22. The end walls 18 and 20 extend angularly in approximately perpendicular planes and the sides of the end walls are integrally joined by spaced side walls 24 and 26 which function to prevent the end walls from spreading apart as pressure is exerted thereon by the finger. A recessed portion 25 is formed in the free edge of each side wall 24 and 26 to provide clearance between such walls and the periphery of the ball 10 when the support is fitted on the finger. It will be understood that straps or other reinforcing members (not shown) could be provided to reinforce the end walls so as to enable such walls to withstand the forces exerted thereon. The support member may be formed from any material, such as metal or plastic, that is sufficiently rigid, in thin sections, to withstand the pressure applied thereto, and which will not

rust or corrode when in contact with moisture or perspiration.

Since the outer portion of the end wall 18 extends partially into one of the finger passageways, the walls, in cross-section, are sufficiently thin to enter such passageways when positioned on the finger without marring or otherwise damaging the material from which the bowling ball is formed and without interfering with the user's normal handgrip of the ball. Such a thin-sectioned construction also permits the support to be shaped, within limits, to fit fingers of various sizes and shapes. The support members may, however, be manufactured in some graduated sizes.

For the purpose of releasably securing the finger support to the finger, so as to maintain such finger in a bent position with the walls 18 and 20 abutting the dorsal surfaces of the finger on each side of the finger joint, one end portion of a strap 28 is fixed to the side wall 24 by any suitable means, such as the rivet 30, the strap being sufficiently long to extend around the finger. A connecting member, generally designated 32 and formed of a single piece of flat type wire, is slidably fitted on the strap 28 and performs the double function of adjusting the effective length of the strap and releasably securing the free end of the strap to the opposite side 26 of the support member. The strap may, of course, be made of any suitable material, and other types of connecting or fastening members may be used, but the illustrated types have been found satisfactory and desirable. A portion 34 of the wire forming the connecting member extends substantially parallel with the axis of the strap 28 while the other portion of the wire is bent in the form of a square wave having spaced transversely extending portions 36, 38, 40 and 42 integrally joined by longitudinally extending portions 44, 46 and 48. The free end of the straight portion 34 is bent in the form of a hook 50 adapted to releasably engage an aperture 51 formed in the side wall 26 adjacent the apex of the support member while the free end of the square wave portion is spliced to the straight portion 34 at a position near, but spaced from, the hook 50.

The strap 28 is interlaced through the oppositely directed, coplanar recesses in the square wave portion of the connecting member 32 so as to overlie the alternate, transversely extending portions 36 and 40 and to underlie the alternate transversely extending portions 38 and 42, while the longitudinally extending portions 44, 46 and 48 and the straight portion 32 prevent transverse movement of the strap relative to the connecting member 32. When tension is applied to the strap 28, the transversely extending portions 36, 38, 40 and 42 of the connecting member 32 resist longitudinal movement of the connecting member relative to the strap.

From the above description, it will be appreciated that the connecting member may be positioned at any desired location on the strap 28 after which the hook portion 50 is positioned in engagement with the aperture 51 in the side wall 26 so that the strap snugly fits the finger and retains the support member on the finger. As shown in Fig. 7, the support member 15 is fitted on the finger when the finger is in a bent position, the letter A designating that portion of the finger which is nearest the knuckles while the letter B designates that portion of the finger which is nearest the fingernail. The support member thus supports the finger so that the bowler will not inadvertently straighten the finger before he releases the ball. After the support member 15 has been positioned on the finger, the hook portion 50 of the connecting member 32 is then inserted in the aperture 51 in the side wall 26 so as to maintain the strap 28 snugly against the finger and retain the support member on the finger.

While a preferred embodiment of the invention has been shown and described, it will be understood that various changes and modifications may be made without departing from the spirit and scope of the invention.

What is claimed is:

1. A finger support comprising a pair of end walls joined at one end thereof, said end walls extending in angular relationship in approximately perpendicular planes, a side wall extending between and rigid with said end walls, and means for releasably securing said support to a finger whereby the inner surfaces of each of said end walls simultaneously abut the dorsal surfaces of the finger.

2. A finger support comprising a pair of angularly extending end walls integrally joined at one end thereof and lying in approximately perpendicular planes, a pair of spaced side walls interconnecting the side portions of said end walls, and means for releasably securing said support to a finger with the inner surfaces of each of said end walls simultaneously abutting the dorsal surfaces of the finger.

3. A finger support comprising a pair of angularly extending end walls integrally joined at one end thereof and lying in approximately perpendicular planes, a pair of spaced side walls interconnecting the side portions of said end walls, said walls formed of relatively rigid, thin-sectioned material which may be shaped within limits to fit fingers of various sizes, and means for releasably securing said support to a finger with the inner surfaces of each of said end walls simultaneously abutting the dorsal surfaces of the finger.

4. A finger support including, in combination, a pair of angularly extending end walls integrally joined at one end thereof and extending in substantially perpendicular planes, each of said end walls shaped to fit the dorsal surfaces of a finger, a pair of spaced side walls integrally joining the side portions of said end walls, and means for releasably securing said support to a finger with the inner surfaces of each of said end walls simultaneously abutting the dorsal surfaces of the finger, said last mentioned means comprising a connecting member formed of a single piece of wire, a portion of the wire extending in a substantially straight line and having a hook on the free end thereof adapted to engage an aperture in one of said side walls, the other portion of the wire bent to form a plurality of adjacent, open-sided, oppositely directed recesses lying in a substantially flat plane, and an elongated flexible strap interlaced through the recesses formed by the wire, one end of said strap fixed to the other of said side walls, said connecting member performing the double function of adjusting the effective length of said strap and releasably securing one end portion of said strap to one of said side walls.

5. A finger support including, in combination, a pair of angularly extending end walls integrally joined at one end thereof and extending in substantially perpendicular planes, each of said end walls shaped to fit the dorsal surfaces of a finger, a pair of spaced side walls integrally joining the side portions of said end walls, each of said side walls having a recess in the free edge thereof, and means for releasably securing said support to a finger with the inner surfaces of each of said end walls simultaneously abutting the dorsal surfaces of the finger, said last mentioned means comprising a connecting member formed of a single piece of wire, a portion of the wire extending in a substantially straight line and having a hook on the free end thereof adapted to engage an aperture in one of said side walls, the other portion of the wire bent to form a plurality of adjacent, open-sided, oppositely directed recesses lying in a substantially flat plane, and an elongated flexible strap interlaced through the recesses formed by the wire, one end of said strap fixed to the other of said side walls, said connecting member performing the double function of adjusting the effective length of said strap and releasably securing one end portion of said strap to one of said side walls.
